NEGATIVE FEED-BACK TRANSMISSION
SYSTEMHenry P. Thomas, Fayetteville, N. Y., assignor to
General Electric Company, a corporation of
New York

Application April 30, 1947, Serial No. 744,845

9 Claims. (Cl. 332—18)

1

My invention relates to a transmission system employing negative or degenerative feedback, and it has particular utility in a system for improving the stability and fidelity of an angularly-modulated transmitter of the phase or frequency modulation type.

It is an object of my invention to provide an improved degenerative feedback system for increasing the stability and linearity of a signal channel including both an amplifier which is supplied with modulation frequency signals and a modulator which develops a high frequency modulated output wave.

Another object of my invention is to provide a selective feedback network for a high frequency modulation system which is particularly effective to stabilize the operation at lower modulation frequencies, thereby realizing the reduction in distortion and hum which is characteristic of a negative feedback system, without adversely affecting the over-all gain-frequency characteristic of the system.

Still another object of my invention is to provide an improved selective negative feedback system which is particularly adapted to the requirements of a phase or frequency modulation network.

A still further object of my invention is to provide an improved selective degenerative feedback network for a frequency modulation system in which undesirable regeneration, which might otherwise occur due to excessive phase shifts at high modulating frequencies, is prevented without adversely affecting over-all gain-frequency characteristics of the system.

The features of my invention which I believe to be novel are set forth with particularity in the appended claims. My invention itself, however, together with further objects and advantages thereof, may best be understood by reference to the following description taken in connection with the accompanying drawings, in which Fig. 1 is a circuit diagram, partly in simplified block form, illustrating one application of my invention to a carrier wave transmitter of the angularly modulated type; and Fig. 2 is a generalized schematic diagram which will be referred to in analyzing certain fundamental principles underlying my invention.

In one embodiment of the present invention there is provided a radio transmission system which may, for example, be of the frequency-modulation type, employing negative feedback in the system. A "feedback" network, for a translating system receiving a main applied sig- 50

nal from a source, is a network adapted to apply to the input terminal of the system, along with the main applied signal, a signal derived from the output terminal of the system. If the signal thus fed back is opposed to the main signal, that is, if one is increasing when the other is decreasing, then the feed back network is acting as a "negative" or "degenerative" feedback network. As is well-known to the art, one of the various advantages of negative feedback is that the linearity of the system is improved. That is, there is more of a tendency for the output signal to be a faithful reproduction of the main applied signal, rather than a distorted reproduction thereof.

In the absence of certain additional features to be mentioned, considerable difficulty would be encountered from the fact that under certain conditions, more particularly at certain relatively high frequencies, there is a tendency for the feed-back signal to said, rather than oppose the main applied signal, as will be understood by those skilled in the art from considerations of phase shift within the system. When the feedback signal aids the main applied signal, there is a condition of positive feedback or regeneration, and a tendency for self-oscillation of the system, which is undesirable in this system.

One embodiment of the present invention may be viewed as having signal-translating means, a first network through which the main signal is applied to the input terminal of the signal-translating means, and a second network through which a signal is fed back from the output terminal to the input terminal. The feedback network of the present invention is adapted to feed back a smaller signal at high frequencies than at low frequencies, which is advantageous in avoiding self-oscillation at those high frequencies where the feedback would become aiding or regenerative. If a smaller signal is fed back at one moment than at another moment, however, there would be a tendency for the total amplification of the system to vary, which would be undesirable. As a special feature of one embodiment of the present invention, there is provided another network which is interposed between the source of the main signals and the input terminal of the signal translating means, and this last-mentioned network is adapted to control the amplitude of the main signal applied to the input terminal of the signal-translating means so that a relatively large main signal is applied at low frequencies when the negative feedback signal is large, and a smaller signal is applied at higher

frequencies when the negative feedback signal is small. Since the main applied signal and the feedback signal are opposed to one another, the net applied signal and hence the output signal are determined by their difference. The correlation of the two networks may be adjusted so that the amplification of the entire system is constant under various conditions of operation. Hence negative feedback is utilized with its attendant advantages, while self-oscillation and variations in the amplification are prevented, as desired.

In the radio transmitter illustrated in Fig. 1, audio modulation signals are impressed upon the input terminals 10 of audio frequency amplifier 11 from any suitable signal source, not shown. This source may, for example, comprise a studio microphone and suitable pre-amplifiers and audio pre-emphasis networks commonly employed in frequency modulation broadcasting practice. The amplified audio signals appearing across the anode load resistor 22 are impressed through blocking capacitor 13 upon a frequency selective network serially including resistors 14, potentiometer 15 and coupling capacitor 16, the function and operation of which will be described in detail presently.

Potentials appearing across the lower portion of potentiometer 15 and across capacitor 16, between an adjustable tap 17 and ground, are impressed upon the control grid of a second audio amplifier 12. A direct current grid return is provided in shunt to the capacitor 16 by the relatively high resistance 18 and suitable operating bias for the amplifier 12 is provided in conventional manner by the cathode bias resistor 19 shunted by the usual audio bypass capacitor 20.

The remaining circuits of the transmitter proper may be entirely conventional and are therefore represented only in simplified block form. The amplified audio signals at the output of amplifier 12 may be further amplified in an audio power amplifier 25 before they are impressed upon a frequency modulator 26. The modulator 26 may be any one of a number well known to the art. For example, it may comprise a modulation system of the type shown in application Serial No. 632,977, Francis M. Bailey, filed December 5, 1945, now Patent No. 2,461,250, issued February 8, 1949, and assigned to the same assignee as the present invention. In this type of system, a special tube and circuits is used for modulator 26 and the mean carrier frequency is controlled by means of a crystal oscillator 27.

The angularly-modulated output wave from modulator 26 is multiplied to a suitable carrier frequency in conventional manner by a plurality of frequency multipliers, indicated by the blocks 28 and 29. The modulated carrier wave is then amplified in the radio frequency power amplifiers 30 before being supplied to the radiating antenna 31.

In accordance with my invention, a degenerative or negative feedback path is provided between a point in the high frequency channel following the modulator 26 and the input of the audio amplifier 12. The input to the feedback network may be supplied from any suitable point at which the frequency is such that the carrier wave may be readily amplified and demodulated, and so connected that the polarity is such that the feedback to amplifier 12 is degenerative. As shown in Fig. 1, it is supplied from a point 32 between the frequency multipliers 28 and 29, each of which may have one or more stages.

The signals may be first amplified in a conventional high frequency amplifier 35, and are then supplied to a well known form of frequency discriminator network 36. As illustrated, this discriminator is of the type shown in Patent 2,121,103—S. W. Seeley, granted June 21, 1938, although many other suitable types are known to the art.

The demodulation components are supplied through blocking capacitor 37 to a second frequency selective network which comprises resistor 38 and capacitor 16. Capacitor 16 therefore acts as a common coupling impedance for both the audio input signals and the feedback signals supplied to the grid of amplifier 12.

Since a considerable amount of phase shift at the higher modulating frequencies is inevitably introduced by the high frequency circuits of the modulator 26 and following circuits, the feedback may become regenerative at these frequencies even though the feedback network is supplied from a proper point to provide degenerative phase, at the grid of amplifier 12, at the lower modulating frequencies. This of course cannot be tolerated because it will produce circuit instability and parasitics, defeating the purpose of the feedback network. Consequently, the frequency selective network 38—16 is employed to provide a gain-frequency characteristic which varies substantially inversely over the audio frequency range. In a modulation system of the type shown in the aforesaid Bailey application, or an Armstrong phase modulator, the audio frequency distortion is a function of the angular excursion caused by the applied modulating signal. For a fixed percentage modulation of the entire frequency modulation system, the angular excursion of the modulator is inversely proportional to the modulating frequency. Hence, the most severe distortion occurs at the lowest modulating frequency. For this reason, the use of negative feedback at only the lower frequencies is still fully effective in reducing distortion. The effect of undesirable hum frequencies, which are commonly encountered in transmitters due to the use of alternating current filament supplies, is also generally most severe at the lower harmonics of the power supply frequency, such as 120 cycles and 360 cycles per second, for example. Therefore the negative feedback at lower audio frequencies is also effective in suppressing these effects. In fact, I have found in practice that the direct current filament supply for modulator 26, previously required, can be eliminated and alternating current supplies used throughout the transmitter.

As a practical matter, I have found that it is satisfactory to design the frequency selective network 38—16 to attenuate substantially the higher modulating frequencies above about 400 to 1000 cycles per second but to pass frequencies below this value without substantial attenuation. Expressed another way, the time constant of this network, that is, the product of its resistance by its capacity, may correspond to the period of a medium audio frequency of the order of about 400 to 1000 cycles per second. However, when the feedback is reduced or cut off at the higher modulating frequencies, the relative gain and degree of modulation increases. In accordance with my invention, this is corrected by the inverse frequency characteristic network 75 comprising the frequency selective network,

14-15-16. If the time constant of this network is made equal to that of the network 38-16, that is, if the resistors 14 and 15 in series have the same resistance as resistor 38, then the tap 17 may be adjusted so that the over-all gain of the system is substantially the same over the audio frequency band.

For a more detailed analysis of the adjustment and operation of the feedback system, reference is now made to the generalized circuit diagram of Fig. 2. The source of modulation frequency signals is represented by the block 40 and the first frequency selective network is represented by resistance R_1 and R_2 and the common coupling impedance Z . Resistance R_1 corresponds substantially to resistor 14 in Fig. 1 plus that portion of potentiometer 15 above tap 17 (indicated by point 17a in Fig. 2), assuming that the source 11 is a substantially constant voltage feed. Resistance R_2 corresponds to that portion of potentiometer 15 below tap 17, and impedance Z corresponds to capacitor 16. The entire signal translating network between the input to amplifier 12 and the feedback 32 is represented by the block 41 which is indicated as having an equivalent over-all gain μ at modulation frequencies. The feedback network, corresponding to the amplifier 35 and discriminator 36 of Fig. 1, is represented in Fig. 2 by the block 42 which is indicated as having an equivalent over-all backward gain β at modulation frequencies. The second frequency selective network is represented by the resistance R and the common coupling impedance Z in which resistance R corresponds to resistor 38 in Fig. 1. The relatively high resistance 18 in Fig. 1, which provides a direct current return path between the grid and cathode of amplifier 12, has substantially no effect upon the operation of the feedback system.

Now if the resistances R and R_1 are both made high relative to the resistance of R_2 , the potential of point 17a can be considered to be essentially the same as that of the upper terminal 21 of the common coupling impedance simplifying the network analysis.

With the above definitions and assumptions in mind, the gain of the system, with feedback, between points 17a and 32 is given by the expression:

$$G_1 = \frac{\mu}{1 - \mu\beta} \quad (1)$$

where μ is the gain of the system in the forward direction without feedback, as previously described, and β is the gain of the total feedback circuit. If the system had a gain independent of frequency before the addition of feedback, μ in this expression will be a constant; but with selective feedback the total gain G_1 will vary with frequency. The network R_1 , R_2 , Z is designed to provide a gain-frequency characteristic which is the inverse of that of the system with feedback applied, as will appear later. If the gain of this network is represented by G_2 , then the complete gain of the system from the signal source 40 to the output is represented by:

$$G = G_1 G_2 = \frac{G_2 \mu}{1 - \mu\beta} \quad (2)$$

Assuming for the moment that the impedance Z is a capacitive reactance X_c , the ratio of output voltage e to input voltage e_0 of the second selective network R , Z is given by the expression:

$$\frac{e}{e_0} = \frac{-jX_c}{R - jX_c} \quad (3)$$

6 The total feedback gain is then a constant β (the gain of network 42) times this expression:

$$\beta_1 = \beta \frac{-jX_c}{R - jX_c} \quad (4)$$

The gain G_1 of the system between points 17a and 32 in the presence of feedback is then:

$$G_1 = \frac{\mu}{1 - \mu\beta \frac{-jX_c}{R - jX_c}} \quad (5)$$

The gain G_2 through the network R_1 , R_2 , Z is given by the expression:

$$G_2 = \frac{R_2 - jX_c}{R_1 + R_2 - jX_c} \quad (6)$$

If $R_1 + R_2$ is made equal to R so that the two frequency selective networks have the same time constant, then:

$$G_2 = \frac{KR - jX_c}{R - jX_c} \quad (7)$$

where:

$$K = \frac{R_2}{R_1 + R_2} \quad (8)$$

Then the total system gain from signal source 40 to the output point 32 is:

$$G = G_1 G_2 = \frac{\mu \frac{KR - jX_c}{R - jX_c}}{1 - \mu\beta \frac{jX_c}{R - jX_c}} \quad (9)$$

$$G = \mu \frac{KR - jX_c}{R - jX_c (1 + \mu\beta)} \quad (10)$$

$$G = \mu K \left[\frac{R - 1/K(jX_c)}{R - (1 + \mu\beta)(jX_c)} \right] \quad (11)$$

The gain will be independent of frequency if:

$$K = \frac{1}{1 + \mu\beta} \quad (12)$$

and will have a value:

$$G = K\mu \quad (13)$$

In other words, the gain-frequency characteristics of the system will be restored to the value without feedback if:

$$\frac{R_2}{R_1 + R_2} = \frac{1}{1 + \mu\beta} \quad (14)$$

It is possible to use a considerable number of variations in these networks and still maintain the desired inverse characteristics. For instance, it can be seen directly from Equation 11 that the simple capacitor used for the common coupling impedance may be replaced by a general impedance Z and if the relations of Equations 12 and 14 are still maintained, the gain will still be independent of frequency. For instance, the impedance Z might be a series circuit of inductance and capacity which could be selected to give essentially infinite attenuation in the feedback circuit at any particular desired frequency merely by adjusting the series resonance of L and C so as to occur at that frequency. This may be advantageous in reducing the gain of the feedback circuits to a very low value at the frequency at which the phase shift through the system becomes 180 degrees, thus preventing instability of the system.

Merely by way of illustration, not in any sense by way of limitation, I have found the following 75 values of circuit constants to be satisfactory in

7
the practical application of my invention to a frequency modulation transmitter:

Audio band width=50-15,000 cycles per sec.
Resistor 14=200,000 ohms
Resistor 15=100,000 ohms
Resistor 38=300,000 ohms
Capacitor 16=.0082 mfd.
Resistor 18=1 megohm

While I have shown a particular embodiment 10 of my invention, it will of course be understood that I do not wish to be limited thereto since various modifications may be made, and I contemplate by the appended claims to cover any such modifications as fall within the true spirit 15 and scope of my invention.

What I claim as new and desire to secure by Letters Patent of the United States is:

1. In a transmitter of angularly-modulated high frequency waves, a source of modulation signals extending over a relatively low-frequency band, a signal translation channel having an input connected to said source and having an output, said channel including means for generating 20 said high frequency waves and modulating them in accordance with said signals, means for demodulating said angularly-modulated waves at said output to develop demodulated signals, a frequency-selective network having an inverse gain-frequency characteristic over said band, 30 means for feeding back said demodulated signals through said network to said input in degenerative phase, whereby the relative degree of modulation at said output is increased at higher modulation frequencies, and a second frequency-selective network in the connection between said source and said input including a coupling impedance across said input common to both said networks, said second network having a correlated gain-frequency characteristic which substantially restores the relative degree of modulation at said output to the value without feedback.

2. A modulation system comprising, in combination, a high frequency signal modulator having a predetermined gain-frequency characteristic and having an input and an output, a first frequency-selective network, means for impressing potentials within a band of modulation frequencies on said network, an impedance in said network coupled to said input, a negative feedback network comprising means for deriving potentials at modulation frequencies from said output and a second frequency selective network, said second network also including said input coupling impedance, each of said networks having maximum gain at a relatively low frequency in said band and decreasing gain at higher modulation frequencies, and means to adjust the relative amplitudes of said potentials impressed on said input from said frequency-selective networks, whereby the effect of said feedback network upon said gain-frequency characteristic at said output may be substantially compensated.

3. In a wave transmission system, a signal translating network having an input and an output and a forward gain μ over a predetermined operating frequency range, a frequency-selective network serially comprising a relatively high resistance R_1 , a relatively low resistance R_2 and a coupling impedance, said input being connected across said resistance R_2 and said impedance in series, means for impressing signals within said frequency range across said network, a negative feedback network having input and output ter-

5
minals and having backward gain β over said range, a second frequency-selective network serially comprising a relatively high resistance R and said impedance, means coupling said output to said input terminals, and means for impressing signals from said output terminals across said second network, the values of said resistances substantially satisfying the equations $R=R_1+R_2$ and

$$\frac{R_2}{R_1+R_2} = \frac{1}{1+\mu\beta}$$

whereby the frequency response characteristic of said system is substantially unaffected by said feedback over said range.

4. In a wave translating system, a signal translating path having a gain μ between input and output terminals, a signal frequency source having an output, a first frequency-selective network composed of a relatively high resistance R_1 , a relatively low resistance R_2 and a coupling reactance in series, said input terminals being coupled across said resistance R_2 and said reactance in series, means for impressing signals from said source across said first network, and a negative feedback path having a gain β between its input and output, said input being coupled to said output terminals and said output being coupled across a second frequency-selective network composed of a relatively high resistance R in series with said coupling reactance, in which both said networks have substantially the same time constant and in which the relationship

$$\frac{R_2}{R_1+R_2} = \frac{1}{1-\mu\beta}$$

35
is substantially satisfied.

5. In a modulation system, the combination of 40 a source of modulation signals lying within a relatively low frequency band, a signal translating channel having an input and an output and comprising an amplifier for said signals and a modulator for producing high frequency signal-modulated waves at said output, a first frequency selective network, means to supply said modulation signals to said input through said network, a negative feedback network supplied from said output and comprising means to demodulate said waves and to develop demodulated signals lying within 45 said band, a second frequency selective network, means to supply said demodulated signals back to said input through said second network in degenerative phase, each of said frequency-selective networks having substantially the same time constant and having an inverse gain-frequency 50 characteristic over said band, whereby the relative degree of modulation at said output tends to be increased at higher frequencies within said band due to said feedback, and means to adjust the relative amplitudes of said signals supplied to 55 said input from said first and second networks, whereby the effect of said feedback network upon the relative degree of modulation may be substantially compensated.

6. In a modulation system, the combination of 60 a source of audio frequency signals, a signal translating channel having an input and an output, said channel comprising an audio amplifier supplied from said input and a modulator for producing high frequency waves modulated by said signals at said output, a first frequency selective network comprising a potentiometer and a coupling impedance serially connected across said source, said network having a gain which 70 varies inversely with frequency over the audio

range, means for impressing audio signals appearing across said impedance and an adjustable portion of said potentiometer upon said input, a negative feedback network supplied from said output, said feedback network including means for demodulating said waves and deriving therefrom the audio modulation components, a second frequency-selective network serially comprising a resistor and said coupling impedance, and means for impressing said modulation components across said second network, said second network having substantially the same time constant as said first network.

7. In a wave transmission system, a signal translating network having an input and an output, a frequency selective network serially comprising a resistor and a capacitor, means for supplying audio frequency signals across said network, means for impressing upon said input audio signals appearing across said capacitor and a tapped point on said resistor, a negative feedback network comprising means for deriving signals within the audio frequency range from said output, a second frequency-selective network, and means for impressing said derived signals across said second network, said second network serially comprising a second resistor and said capacitor, both said frequency-selective networks having substantially the same time constant.

8. In a wave transmission system, a signal translating network having an input and an output, a frequency selective network serially comprising a resistor and a capacitor, means for supplying audio frequency signals across said network, means for impressing upon said input audio signals appearing across said capacitor and an adjustable tapped point on said resistor, a negative feedback network comprising means for deriving signals within the audio frequency range from said output, a second frequency-selective network, means for impressing said derived signals across said second network, said second network serially comprising a second resistor and said capacitor, both said frequency-selective net-

works having substantially the same time constant corresponding to the period of a medium-frequency audio wave, and means for adjusting said tapped point to adjust the frequency transmission characteristics of said system.

9. In a carrier wave transmission system, the combination of a signal channel having input and output terminals, said channel comprising an audio amplifier supplied from said input terminals and a modulator for producing high frequency waves modulated by said signals at said output terminals, a source of audio frequency signals, a first frequency-selective network serially consisting of a potentiometer and a coupling capacitor, means for impressing signals from said source across said first network, means for impressing audio signals appearing across said capacitor and a point on said resistor upon said input terminals, a second frequency-selective network serially consisting of a second resistor and said coupling capacitor, a negative feedback network including means for deriving signals within the audio frequency range from said output terminals and impressing them across said second frequency-selective network, both said frequency-selective networks having substantially the same time constant corresponding to the period of a medium audio frequency, whereby the relative degree of modulation at said output terminals tends to be reduced at lower audio frequencies due to said feedback, and means for adjusting said point on said first resistor to compensate for said tendency.

HENRY P. THOMAS.
